[57] CLAIM

The ornamental design for a folding garment hanger, as shown and described.

DESCRIPTION

FIG. 1 is a front elevational view of a folding garment hanger showing my new design, in its open position;

FIG. 2 is a top plan view thereof;

FIG. 3 is a bottom plan view thereof;

FIG. 4 is a side elevational view thereof, each side being the mirror image of the other;

FIG. 5 is a rear elevational view thereof;

FIG. 6 is a front elevational view thereof showing the hanger in its folded condition.

FIG. 5

FIG. 6
